UNITED STATES PATENT OFFICE.

ELIHU C. WILSON, OF LOS ANGELES, CALIFORNIA.

LATCH GUARD FOR CASING-HANDLING TOOLS.

Application filed November 1, 1923. Serial No. 672,103.

To all whom it may concern:

Be it known that I, ELIHU C. WILSON, a citizen of the United States, residing at Los Angeles, in the county of Los Angeles and

5 State of California, have invented new and useful Improvements in Latch Guards for Casing-Handling Tools, of which the following is a detailed specification.

This invention relates to latch guards for 10 casing handling tools and has for its primary object to provide means for guarding latches against accidental unlocking by the action of extraneous bodies, such as cables or rigging customarily suspended in proximity 15 with this class of tools.

While my device is for use in connection 20 with any clamping tool having a certain general type of latch incorporated therewith, such as will be noted later, I have chosen to illustrate my invention in connection 25 with a casing elevator and latch of the type disclosed in my copending application on well elevators, filed April 20th, 1920, Serial Number 375,332. By thus illustrating a practical embodiment of my invention 30 with a definite structure, I may better point out its function and value, but the accompanying illustrations and following description are not in any way to be considered as limitations of the invention.

The casing elevator disclosed in aforementioned copending application, and here illustrated in part, is for the purpose of setting and withdrawing well casings or drill pipe, and mainly consists of two relatively movable clamping members adapted to be swung into and out of casing encircling position and shifted vertically along the casing into bearing with annular shoulders formed by casing collars.

A spring urged, oscillatory latch is provided for locking the two members together, and of necessity, as will be later apparent, the free end of the latch has a clearance from the immediately adjacent portions of the outer peripheral face of one of the clamping members and the nose of the latch is beveled to aid it in riding over certain locking lugs during the closing of the elevator. An opening is thus left between the periphery of the clamping member and the end of the latch, this opening inviting the accidental entrance of cables or the like between clamp member and latch, which en-

trance tends to oscillate the latch to unlock 55 it. The elevator is then free to swing open and drop the work with the liability of disastrous results.

With my device installed, the ends and beveled nose of the latch are protected in 60 such a manner that the entrance of extraneous bodies between latch and latch engaged clamp member is prevented and the guard is so shaped that such foreign bodies are guided over the juncture between latch and 65 elevator body.

I have provided two such guards, one at each end of the latch to protect it top and bottom, and the space between guards leaves ample room for the insertion of the operator's hand or suitable tools for purposely 70 and wilfully oscillating the latch to unlock the elevator.

The construction and arrangement of my device will be more fully set forth in the following detailed description, in which further objects and features of novelty of the invention will be stated. Reference will be had to the accompanying drawings, in 75 which:

Fig. 1 is a perspective view showing my latch guard incorporated with a casing elevator, the latter being in unlocked and opened position; and

Fig. 2 is a view similar to Fig. 1, but 85 showing the elevator closed and locked.

I will first briefly describe the structure of the elevator, proper, but will not attempt to assign definite reasons for certain of the latch elements being shaped and arranged as 90 they are, for these points are fully discussed in my aforementioned copending application and have no direct bearing on the present invention. It will suffice to state that the latch elements are designed to coact in a 95 manner to resist accidental unlocking during vertical movement of the casing and casing elevator, either from vertical vibrations of the well pipe or from stresses and strains which may be put on the elevator during operation.

A gate A is hinged by vertical pin 10 to body member B, the outer end of the gate being free to swing to open and close the elevator. Gate A and body B may be considered as complementary clamping and holding members defining a bore for the reception of a casing or drill pipe, and sus-

pension links (not shown) are adapted to be passed through openings 11 in bifurcated body extensions 12, whereby the elevator may be disposed over the mouth of a well and raised or lowered by the usual hook and tackle in the derrick or rig.

A T-shaped oscillatory latch 13, having a shank 14 and a transverse head 15, is rigid with vertical pivot shaft 16, the latter being journaled in knuckles 16^a on body member B. Latch 13 is adapted to be urged or biased in a counter-clockwise direction, as viewed in the figures, by spring 17, and stop means (not shown) are provided in connection with the body member B to limit latch movement in this direction in order that the latch may not be swung towards the elevator bore sufficiently to interfere with the closing of the elevator.

The longitudinal side face 18 of head 15 forms the nose of the latch and is beveled off so the head will automatically be swung outwardly, as the gate is being closed, by engagement with the curved forward face 19 of vertically spaced locking lugs 20 on gate A. When the gate is fully closed, spring 17 biases latch 13 through an arcuate path into the position of Fig. 2 to lock the elevator, the latch shank 14 then lying between lugs 20 and the locking faces 21 of head 15 seating against lug shoulders 22. Preferably, the locking faces 21 are arcuate and concentric with the latch axis, and shoulders 22 are arcuate and concentric with said axis when gate A is closed.

When in locking position there is necessarily a space between nose 18 and the adjacent surface of gate A, and but for my guard means, ropes, cable rigging or other bodies extraneous to the elevator, are liable to work their way or be accidentally pulled between head 15 and gate A, with the result of oscillating the latch out of locking engagement and allowing the elevator to swing open. The points of engagement between the gate and the ends of the latch head are, of course, most exposed to the entrance of extraneous bodies, and I have therefore provided means for particularly protecting these points. Accidental unlocking of the elevator is apt to be most disastrous, both to operators and work, and I therefore consider my improvement to be of great value both from a safety and economic standpoint.

I provide guard lugs 23 which extend laterally from gate A and are preferably, though not necessarily, integral with lugs 20, there being a guard lug coextensive with each locking lug. When in locking position, the inner lateral face 24 of head 15 is adapted to bear against shoulders 25 of guard lugs 23, these lugs extending sufficiently from the peripheral face of gate A to bring shoulders 25 well beyond the said peripheral face, so head 15, when in the po-

sition of Fig. 2, is spaced an appreciable distance from the elevator body to facilitate the insertion of an operator's hand or a suitable tool between gate and latch when wilful unlocking is to be accomplished. The vertical spacing of lugs 23 gives vertical clearance for the hand or tool in purposely unlocking the elevator.

Now it will be observed that shoulders 25 on the upper and lower guard lugs extend above and below the upper and lower ends of head 15, and that ends 26 of the guard lugs extend beyond and partially around the beveled end or latch nose 18. The horizontal outline of shoulders 25 may be considered as complementary to said face 24 and, to a limited extent, of latch nose 18.

By reason of the above characteristics, guard lugs 23 protect both end and side points of engagement between latch head and gate in a manner to guide extraneous bodies away from these points of engagement and to prevent the entrance of such bodies between the engaged members. Furthermore, the rearwardly inclined or curved faces 27 extending from the peripheral face of the gate to lug ends 26, serve to guide cables and the like away from and over the points of latch engagement to further minimize the chance of accidental unlocking action.

In the drawings, shoulders 25 are shown as serving to limit the counterclockwise or latching movement of the latch when the gate is closed, and may therefore perform the auxiliary function of a stop, but it will be understood, it lies within the scope of my invention to limit such movement by other means, and that the guard lugs will function as such without the existence of a full or even partial bearing between head 15 and shoulder 25. The important characteristics are that shoulders 25 extend vertically beyond the ends of the latch head; that the ends of the guard lugs extend in a manner to prevent the entrance of bodies between the latch nose and gate body, and that the inclined faces of the lugs are formed and arranged to guide cables, or the like, which may strike the peripheral face of the gate, around and over the latch nose.

I may, of course, provide the guard lugs in greater number than that shown or provide a single lug extending vertically from the top of upper shoulder 25 to the bottom of lower shoulder 25, but such provision would cause the partial or total closing of the clearance space between latch and gate, and thus render it more difficult to manually unlock the elevator.

Finally, I wish to repeat the reservation that the illustrations and description are to be considered merely as illustrative and not as restrictive on the broader claims appended hereto, for it will be understood that va-

rious changes in design and arrangement may be made without departing from the spirit and scope of such claims.

Having described a preferred form of my

5 invention, I claim:

1. In casing handling tools, the combination of a plurality of clamping and holding members hinged together and adapted to embrace between them a pipe or casing, an

10 oscillatory latch device pivotally connected with one of said members, said latch device including a shank, a head on the free end of the shank and with its outer longitudinal face forming the nose of the latch, the mem-

15 ber with which said latch is engaged being provided with spaced locking lugs with which said head is adapted to engage and between which the shank thereof is received, spaced guard lugs on the latch engaged

20 clamp member, shoulders on said guard lugs and adapted to be engaged by the inner side face of the latch when in locking position, said shoulders extending longitudinally be-

25 yond the ends of the head, and the ends of the guard lugs extending partially around the nose of the latch.

2. In casing handling tools, the combination of a plurality of clamping and holding members hinged together and adapted to

30 embrace between them a pipe or casing, an oscillatory latch device pivotally connected with one of said members, said latch device including a shank, a head on the free end of the shank and with its outer longitudinal

35 face beveled and forming the nose of the latch, the member with which said latch is engaged being provided with spaced locking lugs with which said head is adapted to engage and between which the shank thereof

40 is received, spaced guard lugs on the latch engaged clamp member, shoulders on said guard lugs and adapted to be engaged by the inner side face of the latch when in lock-

45 ing position, said shoulders extending longitudinally beyond the ends of the head, and the shoulder faces of the guard lugs being curved complementary to the bevel of the latch nose and extending laterally partially around the nose.

50 3. In casing handling tools, the combination of a plurality of clamping and holding members hinged together and adapted to embrace between them a pipe or casing, an oscillatory latch device pivotally connected

55 with one of said members, said latch device including a shank, a head on the free end of the shank and with its outer longitudinal face forming the nose of the latch, the mem-

60 ber with which said latch is engaged being provided with spaced locking lugs with

which said head is adapted to engage and between which the shank thereof is received, spaced guard lugs on the latch engaged clamp member, shoulders on said guard lugs and adapted to be engaged by the inner side 65 face of the latch when in locking position, said shoulders extending longitudinally beyond the ends of the head, the ends of the guard lugs extending partially around the nose of the latch, and the guard lugs being 70 provided with inclined guard faces extending from the body of the latch engaged clamp member to the ends of the guard lugs.

4. In casing handling tools, the combination of a plurality of clamping and holding 75 members hinged together and adapted to embrace between them a pipe or casing, an oscillatory latch device pivotally connected with one of said members, said latch device

including a shank, a head on the free end of the shank and with its outer longitudinal face forming the nose of the latch, the mem-

ber with which said latch is engaged being provided with spaced locking lugs with which said head is adapted to engage and 80

between which the shank thereof is received, spaced guard lugs on the latch engaged clamp member and integral with the locking lugs, shoulders on said guard lugs and

85 adapted to be engaged by the inner side face 90 of the latch when in locking position, said shoulders extending longitudinally beyond the ends of the head, and the ends of the guard lugs extending partially around the nose of the latch. 95

5. In casing handling tools, the combination of a plurality of clamping and holding members hinged together and adapted to

100 embrace between them a pipe or casing, an oscillatory latch device pivotally connected with one of the members, the latch device including a shank, a latch and handle head

on the free end of the shank with its outer longitudinal face forming the nose of the latch, the member with which said latch is 105

engaged having a locking lug engageable by said head, and having stop means to limit the movement of the head toward said mem-

ber so as to leave a space between the member and head for manipulation of the latch, 110 and spaced guard lugs on said member lo-

115 cated near the ends of the head and extending partially around the nose of the latch to guard the hand space between the said mem-

In witness that I claim the foregoing I have hereunto subscribed my name this 20th day of October 1923.

ELIHU C. WILSON.
